[57] CLAIM

The ornamental design of a foot for legs of a portable seat, as shown and described.

DESCRIPTION

FIG. 1 is a perspective view of a foot for legs of a portable seat, showing my new design;

FIG. 2 is a side view of a foot for legs of a portable seat; FIG. 3 is a top view of the foot;

FIG. 4 is a bottom view of the foot;

FIG. 5 is a front view of the foot; and

FIG. 6 is a rear view of the foot.

The broken lines showing the portable seat is for illustrative purposes only and forms no part of the claimed invention.
